TILT TABLE

John G. Wallace, Toronto, Ontario, Canada

Application May 11, 1945, Serial No. 593,271

7 Claims. (Cl. 311—37)

1

My invention relates to improvements in tables of the class in which the top is supported by a frame devised to enable it to be tilted to any desirable angle and also to be raised or lowered. In particular the invention appertains to a table in which the frame is composed of metal bars and in which the bars include telescopic parts by which the frame is adjustable to raise or lower the top.

The object of the present invention is to provide a table of the character above referred to in which the top can be tilted and/or set at different heights by means of a bar frame incorporating a novel combination and arrangement of telescopic and swivel parts.

The invention is illustrated in the accompanying drawing in which:

Fig. 1 is a front elevation of the table.

Fig. 2 is a top plan view thereof.

Fig. 3 is an end elevation of Fig. 1.

Fig. 4 is a detail showing a swivel connection between the base of the frame and one of the uprights or legs.

Fig. 5 is a perspective view of the lower portion of the frame.

The invention is shown and will be described as an overbed table. The top, denoted at 6, is an ordinary member presenting a flat upper surface which may be supplied with a marginal rim as depicted. Said top is of a rectangular configuration, being in the present instance of a greater length than width.

The metal frame is composed of tubular bars, there being provided a front member and a back member, both of a U-shape in configuration and united at the base portions. These members extend parallel to each other and longitudinally of the top 6. The front member comprises an upper section 7, a lower section 8 and a side section 9 which forms a leg or upright at an end of the top 6. Said side section is a telescopic element consisting of a rigid upward continuation 10 of the lower section 8 and a downward continuation 11 of the upper section 7 slidably arranged for vertical extensile movement and adapted to be clamped in a set position as by a clamp 12. Any suitable clamp device may be employed. In the present instant this is formed by slotting the upper end of the part 10, as at 13, and providing ears 14 on the slotted portion connected by a handled screw 15 by which they can be drawn together to apply clamping pressure on the telescoping part 11.

The upper section 7 is loosely sleeved in bearings 16 secured to the under side of the top 6

2

to provide a swivel or hinged connection therewith, conventional means being used to prevent end play of said section in the bearings.

The back member is similar in construction to the front member and comprises an upper section 17, a lower section 18 and a side section 19 forming a leg or upright which is telescopic. This leg or upright consists of the telescoped parts 20 and 21 which are adapted to be secured together 10. by a clamp 22 similar to that previously described.

The part 20 is a downward continuation of the upper section 17 and is journaled in bearings 23 attached to the under side of the top 6 to provide a swivel or hinged connection therewith. 15 The part 21 is an upward articulate continuation of the lower section 18 and has a swivel juncture 24 therewith so that it may swing to and away from the front member 9. The swivel juncture may consist of interfitting elements having a 20 common retaining device 25.

The lower section 8 of the front member 9 and the corresponding section 18 of the back member 19 are rigidly tied together as by the crossbars 26.

25 From the preceding description it will be manifest that the invention provides an adjustable table that can be placed over a bed, and one in which the top can be raised or lowered by the use of the clamping devices on the telescopic legs. 30 Additionally the top can be tilted to any desirable angle by raising one of the legs to a greater height than the other. In doing so the leg 19 swings from its swivel connection 24 to accommodate the hinge movement of the top which is the important 35 feature of construction.

What I claim is:

1. In a tilt table, a top having a front edge and a supporting frame therefor, said frame comprising a base part for resting upon a supporting 40 surface, and spaced upright members forming a connection between said top and said base part, and arranged one in advance of the other with respect to the front edge of said top, the lower end of one of said upright members being rigid 45 with said base part and the upper end thereof being hingedly related to said top, and the other upright member being formed with lower and upper sections permitting of telescopic adjustment, said upper section thereof being hinged to said top, and said lower section thereof being hinged to said base part to provide a pivot whereby the last mentioned upright member is free to move angularly to and away from the other upright member in setting said top to different angles by 50 the use of said telescopic adjustment.

2. In a tilt table, a top having a front edge, and a supporting frame for said top, said frame comprising a base part for resting upon a supporting surface, spaced upright bars forming a connection between said top and said base part and arranged one in advance of the other with respect to the front edge of said top, the lower end of one of said bars being rigid with said base part and the other end thereof being hinged to said top, the other of said bars having telescopic sections and being hingedly connected to said top and to said base part to move angularly out of perpendicular in setting said top to different angles by means of said telescopic sections, and locking means for said telescopic sections.

3. In a tilt table, a top having a front edge, and a supporting frame for said top, said frame comprising a base part for resting upon a supporting surface, spaced upright bars forming a connection between said top and said base part and arranged one in advance of the other with respect to the front edge of said top, said bars having telescopic sections, the lower end of one of said bars being rigid with said base part and the other end thereof being hinged to said top, the other bar being hinged to said top and to said base part so that it may swing to accommodate telescopic adjustment of one of the bars relative to the other in the tilting of said top, and means for releasably locking together said telescopic sections of each of said bars.

4. A tilt table comprising a top, and a supporting frame, the frame being made up of a base part, a pair of tubular members upstanding therefrom and disposed one in advance of the other, either of said members have upper and lower sections for telescopic action, said members being bent at right angles at their upper ends to extend parallelly beneath said top transversely thereof to form horizontal sections, bearings loosely sleeved on said horizontal sections to hingedly attach them to said top, the lower section of one of said members being rigid with said base part and the lower section of the other member being hingedly connected to said base part, and means for releasably locking said upper and lower sections together when telescopically adjusted.

5. A tilt table comprising a top, and a frame made up of tubular bars providing U-shaped front and back members having upper, lower and side sections, the side sections being erectile to form legs, the upper and lower sections being

horizontal and having continuations bent to form said side sections and slidably interfitting for extensible movement, one of the continuations of the lower sections being rigid and the other being sleeved to form a swivel joint, crossbars rigidly uniting said lower sections, bearings loosely sleeved on said upper sections and swivelly attaching them to the underside of said top, and means for releasably locking said slidably interfitting continuations of which said side sections are severally composed.

6. A tilt table comprising a top, and a supporting frame, the frame consisting of a stable base, a pair of legs having telescopic lower and upper parts, said legs being disposed one in advance of the other and the lower part of one of them being rigid with said base and the lower part of the other one being swivelly connected to the base so that this leg may swing bodily out of the perpendicular, means for securing the telescopic parts of the legs in set position, and means swivelly attaching the upper part of each leg to said top so that parallel axes are provided by which said top can be tilted by telescopic adjustment.

7. In a tilt table of the class described comprising a U-shaped rigid tubular base having a pair of tubular bars extending vertically from the ends of the U, a pair of L-shaped tubular bars having their vertical leg-forming sections telescoped within said vertical tubular bars, a table top pivotally secured to said L-shaped bars, and means at the upper ends of said vertical tubular bars for securing said leg-forming sections whereby to lock said L-shaped bars in any desired position; the improvement including means for enabling said vertical tubular bars to have relative angular adjustment to accommodate tilting of said table top, said means including a pivotal connection between one of said vertical tubular bars and an end of said U of the said base.
